RAILWAY PILOT COUPLER

William H. Meyer, St. Louis, Mo., assignor to General Steel Castings Corporation, Granite City, Ill., a corporation of Delaware

Application November 1, 1947, Serial No. 783,522

6 Claims. (Cl. 213—4)

1

The invention relates to locomotive pilot and coupler structure of the type in which the coupler swings vertically from an extended functioning position to a retracted non-functioning position.

The main object of the present invention is to facilitate movement of the coupler structure from one position to another. In one form of the invention, the weight of the coupler is counterbalanced by a spring. In another form of the invention, a screw is used to move the coupler from one position to another.

One coupler used heretofore was counterbalanced by a weight at its rear end opposite the coupler head and was pivoted near its center to the pilot. With this arrangement, a relatively deep recess is required at the rear of the coupler pivot to accommodate the coupler counterbalancing weight.

Another object of the invention is to reduce the overhang of the pilot to a minimum and to eliminate the weight and cost of the heavy counterbalance previously used and to provide for retractile couplers on existing locomotives having relatively shallow pilots and non-retractile couplers without changing the present pilot beam and coupler.

Another object is to retract the coupler into a pilot recess by swinging it upwardly. A further object is to provide a substantially rigid pilot portion of maximum height below the coupler recess to resist the thrust on the pilot when it strikes an object in the path of the locomotive.

These and other detail objects as will appear from the following description are attained by the structure illustrated in the accompanying drawings, in which:

Figure 1 is a top view of a locomotive pilot beam, pilot and coupler structure, the rear end of the pilot being broken away and the coupler structure being shown in functioning positions.

Figure 2 is a front elevation of the structure shown in Figure 1, the coupler being in non-functioning position and a suitable plate closing the coupler recess opening.

Figure 3 is a longitudinal vertical section taken approximately on the line 3—3 of Figure 1.

Figure 4 is a similar section taken approximately on the line 4—4 of Figure 2.

Figure 5 is a detail section taken on the line 5—5 of Figure 3.

Figure 6 is a similar section drawn to an enlarged scale and showing some of the parts in Figure 5.

Figures 7 and 10 are top views of locomotive front end structure and show other forms of the invention.

2

Figure 8 is a front elevation showing the embodiment of Figure 7 and showing a portion of the coupler structure in section.

Figures 9 and 11 are longitudinal vertical sections taken approximately on line 9—9 of Figure 7 and line 11—11 of Figure 10, respectively.

Referring to Figures 1—4, the pilot beam 1 is shown attached to the front end of the locomotive main frame 2 and mounts for vertical adjustment a relatively short locomotive pilot 3. The pilot front walls 4 provide an obstacle deflecting surface and converge forwardly of the locomotive and merge with each other and with the pilot end walls 5. The pilot includes a recess 7 having a relatively small opening in front walls 4 and having a bottom wall 7a, side walls 7b, and a rear wall 7c. The portions of pilot front walls 4 below recess 7 are rigid and integral.

The coupler structure carried by the pilot includes a coupler pocket 8 within recess 7 and mounted on the pilot for vertical movement about a horizontal pivot 9 and mounting a coupler 10, including a head 11 and a shank 12, for horizontal movement about a vertical pin 13 (Figures 1 and 3). A portion of the lower face of coupler head 11 is slidably mounted on a forwardly extending flange 8a on the coupler pocket. Coupler 10 swings vertically with coupler pocket 8 about the horizontal pivot 9 between functioning position, in which the coupler head 11 extends forwardly of the pilot, as shown in Figures 1 and 3, and retracted non-functioning position, as shown in Figures 2 and 4. A closure plate 14 formed integral with coupler pocket 8 closes the recess opening when the coupler is in retracted position. A compression spring 17 counterbalances the coupler to facilitate its movement from one position to the other. A web 15 on coupler pocket 8 pivotally mounts an arm 16 seating one end of spring 17 and including a cylinder 18 encircling spring 17 to guide the spring as it is compressed. The other end of spring 17 is seated on a seat 19 mounted on a rearward extension 20 rigid with the pilot. Seat 19 is adjustable to vary the spring compression. The spring compression preferably is adjusted to substantially balance the coupler structure about its pivot 9.

The device for adjusting the spring compression comprises a threaded sleeve 21 rotatably mounting spring seat 19 and having a hexagonal portion 22 forming a stop for the spring seat. Sleeve 21 is threaded into an adjusting block 23 engaging a concave bearing 24 on extension 20 and mounted for pivotal movement relative thereto. Spring tension is adjusted by rotating sleeve 21 in block 23 to move seat 19 towards or

3

away from arm 16. A lock nut 25 is threaded on sleeve 21 and abuts adjusting block 23.

A rod 26 aligns arm 16 and seat 19 and extends axially of spring 17 and is threaded into arm 16 and is locked thereto by a nut 27. Rod 26 is slidably mounted in sleeve 21 and extends rearwardly thereof when the coupler is in functioning position. A recess 34 (Figure 2) in the lower edge of closure plate 14 receives the forward end of arm 16 when the closure plate is in non-functioning position.

The coupler structure is locked in functioning and in non-functioning positions by an elongated bar 28 extending longitudinally of the pilot and mounted for pivotal movement about its rear end received in a depression 7d in pilot wall 7a. The forward and rearward lower faces of bar 28 rest on wall 7a of the pilot and substantially the entire upper face of bar 28 engages closure plate 14 when the coupler is in extended operative position (Figure 3). A spring urged plunger 30 is supported by rear wall 7c of the pilot and by a rearwardly extending bracket 29 rigid with wall 7c. Plunger 30 urges bar 28 forwardly relative to the pilot until a depending pin 31 on bar 28 is received in a notch 32 (Figure 6) in wall 7a of the pilot. To release the coupler structure, bar 28 is grasped by its handle 28a and is moved rearwardly manually until pin 31 is free of notch 32 and bar 28 is pivoted horizontally about its rear end until pin 31 is aligned with a slot 33 on the longitudinal center line of the pilot and in wall 7a. In this position, bar 28 may be moved forwardly and be removed from the pilot and the coupler structure be moved from operative to inoperative position. Bar 28 then is installed on the pilot by engaging plunger 30 with the rear end of the bar and passing pin 31 rearwardly through slot 33. Bar 28 is shifted horizontally to locking position with pin 31 in notch 32. The upper forward portion of bar 28 then engages the lower end of closure plate 14 (Figure 2) and locks the coupler structure in inoperative position.

In Figures 7, 8 and 9, a pilot 61, having a recess 61a opening forwardly of the pilot, is mounted by bolts 65a on a pilot beam 62. A coupler pocket 63 is mounted for vertical swinging movement about integral horizontal trunnions 64 pivoted in separate brackets 65 mounted on the pilot beam by bolts 65a for vertical adjustment independently of the pilot. A coupler 66 is mounted on coupler pocket 63 by a vertical pin 67 for relative horizontal pivotal movement. Coupler 66 is movable vertically with coupler pocket 63 about trunnions 64 between functioning position, shown in solid lines in Figure 9, and non-functioning position, shown in dot-dash lines in the same figure. The axes of trunnions 64 and pin 67 preferably intersect at right angles so that the coupler head is positioned a minimum distance forwardly of the pilot beam and the pilot may be relatively shallow and of light weight and of maximum strength for its weight.

A tension spring 68 extends laterally of pilot 61 and balances the weight of coupler 66 as it is moved from one position to the other. Spring 68 is connected at one end to a seat 69 adjustably mounted on the pilot. The opposite end of spring 68 is connected to a seat 69a. A cable 70 is threaded over a pulley 71 rotatably mounted on pilot 61 and is connected at one end to seat 69a and the other end extends through a groove 72 in coupler pocket 63 and is connected to the forward end of coupler pocket 63. A closure plate 75

4

73 integral with coupler pocket 63 closes the recess opening when coupler 66 is in non-function position. A locking bar 74, similar to locking bar 28 in Figures 1-4, holds coupler 66 in both operative and inoperative positions when the locking bar extends longitudinally centrally of the pilot as shown in Figure 7. Locking bar 74 is removed from the pilot by pivoting the bar about its rear end and to the right and passing locking bar pin 75 through slot 76 in the pilot (Figures 7 and 8).

The structure shown in Figures 10 and 11 is similar to that shown in Figures 7-9 except that tension spring 81, which balances the weight of coupler 82, extends transversely below pilot beam 84 and is connected at one end to a seat 83 adjustably mounted on the pilot beam. The other end of spring 81 is attached to a seat 85 having one end of a cable 86 attached thereto and threaded over a pulley 87 rotatably supported by a bracket 88 rigid with pilot beam 84. The opposite end of cable 86 is connected to a coupler pocket 89.

Brackets 90 are integral with the pilot and pivotally support the coupler pocket. Brackets 90 have removable caps 91 to accommodate integral coupler pocket trunnions 93. Caps 91 are inclined on brackets 90 so that buffing forces are transmitted to the rigid portion of the brackets 30 and pulling forces are transmitted partly to the rigid portion of the brackets and partly to the attaching studs 92 instead of entirely to the studs as would result if the caps were vertical.

The structures described facilitate movement of a coupler about its rear end from one position to another. The structures are adapted for use on existing locomotives having relatively short pilots and non-retractile couplers and the present pilot beams and couplers may be used. Each of the pilots has a minimum size opening in its obstacle deflecting walls and an integral portion below the coupler recess opening providing for a stronger pilot structure.

The details of construction may be varied without departing substantially from the spirit of the invention, and the exclusive use of those modifications coming within the scope of the claims is contemplated.

What is claimed is:

1. In combination, a railway vehicle pilot provided with a recess having a forwardly opening end, a coupler device in said recess comprising a head and an elongated shank extending therefrom, said device being arranged for vertical movement about a horizontal pivot between extended functioning and retracted non-functioning positions, a closure plate spaced from said shank and head and movable with said coupler device for closing the recess opening when said coupler device is in non-functioning position, a lock to hold said coupler device in said positions and comprising an elongated bar engageable with said closure plate in either position, and said bar being removable from said pilot to permit said coupler device to be moved from one position to another.

2. In combination, a railway vehicle pilot beam member, a pilot member mounted on said beam member and provided with a recess having a forwardly opening end, a coupler pocket in said recess mounted for vertical movement about a horizontal pivot on said pilot member, a coupler mounted on said coupler pocket for horizontal movement about a vertical pivot on said coupler pocket and movable vertically about said hori-

zontal pivot with said coupler pocket, between a substantially horizontal functioning position and an elevated non-functioning position, a spring anchored at one end to said coupler pocket rearwardly of the coupler pivoted thereon and extending downwardly and rearwardly from the coupler pocket and anchored at the other end to one of said members to counterbalance the coupler and coupler pocket and to facilitate their movement from one position to another.

3. In combination, a railway vehicle pilot provided with a recess having a forwardly opening end, coupler structure comprising a coupler pocket mounted in said recess for vertical swinging movement about a horizontal pivot, and a coupler mounted on said coupler pocket for horizontal swinging movement about a vertical pivot and arranged for swinging movement with said coupler pocket about said horizontal pivot between functioning and non-functioning positions, said coupler pocket having a closure plate rigid therewith and adapted to close the recess opening when said coupler is in non-functioning position, said pilot having a rearward extension, and a compression spring extending longitudinally of the vehicle and connected at one end to said extension and connected at the other end to said coupler structure to counterbalance the coupler and facilitate its movement from one position to another.

4. In combination, a railway vehicle frame provided with a pilot having a recess opening forwardly and upwardly of the vehicle, a horizontal pivot pin within said recess, coupler structure having a rear portion pivoted on said pin and having a forward portion pivoted on said rear portion and projecting substantially horizontally from the recess forwardly of the vehicle and swingable in a horizontal plane when in normal operating position, and a coil spring under compression and connected at its opposite ends to the frame and to the rear portion of the coupler structure rearwardly of the forward portion of the coupler structure and elongating as the coupler structure is swung upwardly and rearwardly from said normal operating position to retracted position.

5. In a railway vehicle coupler and pilot assembly, pilot elements forming a front wall and providing a recess behind the front wall opening forwardly and upwardly of the pilot, a coupler pocket member having a horizontal pivot

on the pilot spaced rearwardly from the pilot front wall, said pocket opening forwardly of the pilot, a coupler having a vertical pivot on said pocket member nearer to the coupler head than said horizontal pivot and in substantial alignment transversely of the pilot with the adjacent portion of the pilot front wall when the coupler is in horizontal functioning position, a closure plate fixedly mounted on said pocket member and extending below said coupler and rearwardly therefrom, when the coupler is in horizontal functioning position, and closing the front of the pilot recess when the coupler and pocket member are swung about the horizontal pivot of the latter to non-functioning position of the coupler, the spring device connecting the rear portion of the pilot to a portion of the closure plate remote from the coupler and counterbalancing the coupler head to facilitate its movement from operative to inoperation position.

6. In combination, a railway vehicle pilot having a forwardly opening recess, a coupler pocket in said recess, a horizontal pivot pin extending through the pilot and pocket and mounting the pocket on the pilot, a coupler in said pocket, a vertical pivot pin mounting the rear end of the coupler in the pocket, a spring device anchored at one end to said pilot and at its other end detachably secured to said pocket, and compressed when said pocket and coupler are in normal operating position and elongating as said coupler and pocket are swung forwardly about said horizontal pivot pin, said horizontal pivot pin and coupler and pocket being removable from said pilot by the withdrawing of said horizontal pivot pin and the detachment of said spring device from said pocket.

WILLIAM H. MEYER.
